(57) **CLAIM**

The ornamental design for a fluid reservoir, as shown and described.

DESCRIPTION

FIG. 1 is a top front isometric view of a fluid reservoir showing the design.

FIG. 2 is a bottom rear isometric view of the fluid reservoir of FIG. 1.

FIG. 3 is a front elevation view of the fluid reservoir of FIG. 1.

FIG. 4 is a rear elevation view of the fluid reservoir of FIG. 1.

FIG. 5 is a left elevation view of the fluid reservoir of FIG. 1.

FIG. 6 is a right elevation view of the fluid reservoir of FIG. 1.

FIG. 7 is a top plan view of the fluid reservoir of FIG. 1.

FIG. 8 is a bottom plan view of the fluid reservoir of FIG. 1.

FIG. 9 is a top front isometric view of the fluid reservoir of FIG. 1 in an alternate position.

FIG. 10 is a bottom rear isometric view of the fluid reservoir of FIG. 1 in the alternate position.

FIG. 11 is a top front isometric view of an alternate embodiment of a fluid reservoir showing the design.

FIG. 12 is a bottom rear isometric view of the fluid reservoir of FIG. 11.

FIG. 13 is a front elevation view of the fluid reservoir of FIG. 11.

FIG. 14 is a rear elevation view of the fluid reservoir of FIG. 11.

FIG. 15 is a left elevation view of the fluid reservoir of FIG. 11.

FIG. 16 is a right elevation view of the fluid reservoir of FIG. 11.

FIG. 17 is a top plan view of the fluid reservoir of FIG. 11.

FIG. 18 is a bottom plan view of the fluid reservoir of FIG. 11.

(Continued)

FIG. 19 is a top front isometric view of the fluid reservoir of FIG. 11 in an alternate position; and,
 FIG. 20 is a bottom rear isometric view of the fluid reservoir of FIG. 11 in the alternate position.

The dashed lines in the drawings illustrate portions of the fluid reservoir that form no part of the claimed design. The shading lines shown in the drawings represent the approximate three-dimensional contour of the claimed design and are not intended to indicate surface decoration.
